UNITED STATES PATENT OFFICE.

NORMAN P. HARSHBERGER, OF CHICAGO, ILLINOIS.

SHINGLE.

Application filed January 27, 1922. Serial No. 532,173.

To all whom it may concern:

Be it known that I, NORMAN P. HARSHBERGER, a citizen of the United States, residing at Chicago, in the county of Cook and State of Illinois, have invented certain new and useful Improvements in Shingles, of which the following is a specification.

This invention relates to shingles and it has for its object the production of suitable means for forming a portion of the shingles and for binding the shingles into bundles. In the application to the roof of certain types of shingles it is sometimes desirable to have certain portions thereof bent or formed into special shapes so as to facilitate the laying of the shingles on the roof. One object of this invention is to provide means not only for assisting in forming the shingles in this particular respect, but in maintaining the particular formation when the shingles are being packed into bundles, and for maintaining the formation until the bundles are unpacked for laying the shingles. The means thus provided are used also for assisting in binding the bundles for convenience in delivering them wherever desired.

Of the accompanying drawings Fig. 1 is a plan view of a shingle such as used in this instance to illustrate and describe the features of my invention; Fig. 2 is a plan view of a similar shingle with certain corners specially formed by bending; Fig. 3 is a plan view of a bundle of shingles as finally bound ready for transportation; Fig. 4 is an enlarged perspective view of one of the elements used in forming and binding the shingles; Fig. 5 is a perspective view of the means which I provide for forming and binding the shingles; and Fig. 6 is a sectional view along the line 6—6 of Fig. 5.

I have illustrated and described a shingle similar to the one illustrated by Fig. 2 in my Patent No. 1,441,420, granted Jan. 9, 1923, and reference may be had thereto for further details in reference to that invention. But, in general, the shingles 10 have slits 11 cut therein and have corners 12 so arranged that, when the shingles are laid on the roof, the corners 12 of one shingle are slipped into the slits 11 of the adjacent shingles so as to keep from bending upwardly the exposed portion 13 of the shingle. And, in order to expedite the laying of the shingles, the corners 14 thereof are bent upwardly so as to allow the corner 12 of the adjacent shingle to be easily passed into the

slit 11. And one of the objects of this invention is to provide means for bending those corners properly and for maintaining them in the bent position until they are laid. The means which I provide for this purpose are also used for binding the shingles into bundles.

In order to suitably bind the shingles I provide any suitable means such as a base 15 to which are fixed posts 16, each of which has a slot 17 therein adapted to hold upright the strip 18. In forming the bundles a wrapper 19, having slots 20 therein, is placed on the base 15 by passing it downwardly with the members 16 and 18 projecting through the slots 20. Each strip 18 has a lug 21 resting on the base 15 upon which the wrapper 19 rests, so that the lug 21 is at all times beneath the wrapper. Each strip 18 also has a wedge-shaped flange 22 which projects outwardly from the surface of the strip at an acute angle, the flanges of the two strips 18 projecting towards each other; and these flanges are so formed as to turn upwardly the corners 14 when the shingles 10 are slipped downwardly over the strips 18 and the posts 16, as indicated in Fig. 6. The lower end of each post 16 has one side 23 wedge-shaped, with the lower forward edge 24 projecting between the flange 22 and the strip 18; and this edge prevents the flange 22 from being bent out of place as the shingles are applied.

In this manner the bundle is built up to the desired size; the entire bundle, including the wrapper 19, is then lifted off from the posts 16; and the wrapper is then wrapped around the bundle with the upper ends of the strips 18 projecting through the slots 25 in the wrapper and the two flanges 26 and 27 of the upper end of each strip are bent in opposite directions to bind the wrapper snugly down onto the shingles. As the wrapper is formed of stiff material this binding of the bundle will be sufficient for rough handling; and the strips 18 will hold the corners 14 in their properly formed condition until the bundles are unpacked.

I claim as my invention:

1. A shingle former comprising a strip adapted to pass through a slit in a shingle, said strip having a tapering flange projecting at an acute angle therefrom, and adapted to bend a portion of said shingle adjacent the slit.

2. A shingle former comprising a strip of

- 2
- stiff material adapted to pass through a slit in a shingle, said strip having a tapering flange projecting at an acute angle therefrom, and adapted to bend a portion of 5 said shingle adjacent the slit, in combination with a post having a slot therein adapted to receive one edge of said strip, and a wedge-shaped portion projecting from said post into the angle formed by said flange and the 10 said strip.
3. A shingle former comprising a strip of stiff material adapted to pass through a slit in a shingle, said strip having a tapering flange projecting at an acute angle therefrom, and adapted to bend a portion of said 15 shingle adjacent the slit, and means for binding together a plurality of said shingles and said strip, said means comprising flanges projecting from the ends of said strip.
4. A shingle former comprising a strip adapted to enter a slit in a shingle, means for holding said strip upright, and a tapering flange projecting angularly from the 20 face of said strip and adapted to bend upwardly one corner of said shingle adjacent said slit as the shingle is passed downwardly with the said strip entering the slit of the shingle.
5. A shingle former comprising a strip 25 adapted to enter a slit in a shingle, means for holding said strip upright, and a tapering flange projecting angularly from the face of said strip and adapted to bend upwardly one corner of said shingle adjacent 30 said slit as the shingle is passed downwardly
- wardly with the said strip entering the slit of the shingle, and means for preventing said flange from bending when said strip is passed into the slits of shingles. 40
6. A shingle former and binder comprising means for bending a portion of each shingle as they are being packed for binding and for holding said bent portions in their bent positions, said means comprising means for binding a plurality of the shingles 45 into a bundle. 50
7. A shingle binder comprising a strip adapted to pass through a slit in a shingle, means fixed to said strip for bending a portion of said shingle adjacent the slit, and said strip having additional means for binding together a plurality of shingles through the slits of which the said strip passes. 55
8. Shingle binding means comprising a wrapper adapted to be wrapped around a bundle of shingles having slits therein, a slit in said wrapper adapted to register with the slit of the shingle on one side of said bundle and a second slit in said wrapper adapted to register with the slit of the shingle on the opposite side of said bundle, and a strip for passing through the slits of said shingles and wrapper with its ends projecting outwardly from said wrapper, and means on the ends of said strip adapted to be bent down snugly against said wrapper. 60
- In testimony whereof, I hereunto set my hand.

NORMAN P. HARSHBERGER.
